(57) **CLAIM**

I claim the ornamental design for a electric hair dressing tool with base, as shown and described.

DESCRIPTION

FIG. 1 is a front of the electric hair dressing tool with base showing my design.

FIG. 2 is a side view thereof;

FIG. 3 is an opposite side view thereof;

FIG. 4 is a top plan view thereof;

FIG. 5 is a bottom plan view thereof;

FIG. 6 is a back view thereof;

FIG. 7 is an upper perspective view thereof; and,

FIG. 8 is an exploded perspective view thereof.
